CABINET FOR A WATER PURIFICATION UNIT

Lawrence C. Oakley, 13647 Calais Drive,
Del Mar, Calif. 92014

Filed Sept. 24, 1973, Ser. No. 400,151

Term of patent 3½ years

Int. Cl. D23—07

U.S. Cl. D23—3

Fig. 1

Fig. 2

Fig. 3

Fig. 4

Fig. 5

FIG. 1 is a perspective view of a cabinet for a water purification unit, showing my new design.

FIG. 2 is an end elevational view thereof as taken from the right hand end of FIG. 1.

FIG. 3 is a front elevational view thereof.

FIG. 4 is a bottom plan view thereof.

FIG. 5 is a perspective view from the rear thereof.

I claim:

The ornamental design for a cabinet for a water purification unit, substantially as shown.
